UNITED STATES PATENT OFFICE.

DAVID W. BROOKS, OF NEW YORK, N. Y., ASSIGNOR TO CONCRETE STEEL COMPANY,
OF NEW YORK, N. Y., A CORPORATION OF DELAWARE.

SOCKET.

1,185,765.

Specification of Letters Patent.

Patented June 6, 1916.

Application filed February 9, 1914. Serial No. 817,428.

To all whom it may concern:

Be it known that I, DAVID W. BROOKS, a citizen of the United States of America, residing in New York city, county and State of New York, have invented an Improvement in Sockets, of which the following description, in connection with the accompanying drawings, is a specification, like letters on the drawings representing like parts.

The present invention is concerned with screw or attaching sockets for use in concrete construction.

The object is to provide a socket of given length and circumference in which a maximum resistance to shearing may be obtained with a comparatively small amount of metal.

A further object of the invention is to improve the facilities for attaching these sockets to concrete forms when the latter are being assembled.

One form of socket embodying my invention is illustrated in the accompanying drawings, in which,

Figure 1 is a vertical section on the dotted line α — α Fig. 2. Fig. 2 is a plan view. Fig. 3 is a view similar to Fig. 1 illustrating a modified form of device intended for use where the concrete body is comparatively thin.

Referring to Figs. 1 and 2 of the drawings the socket there illustrated is seen to comprise a hollow shank portion 1 having an open inner end adapted to provide a flanged top 2 and an interiorly threaded outer end 3. Extending across the interior of the shank is a partition 4 to prevent concrete entering the open inner end from clogging the threaded end. The socket is provided, preferably at or near its outer end with fastening means, shown as in the form of laterally extending ears or projections 5 having notches 6 adapted to receive nails or other fastening means for securing the socket to concrete forms or otherwise in position for embodiment in the concrete as indicated in dotted lines, Fig. 1. The ears 5 are shown as positioned slightly in from the end of the socket. To protect them from breaking upon securing them in position to the forms, they are respectively provided with lugs 7 that project so that their outer surfaces are in a plane with the outer end 55 of the socket. Thus, a blow from a hammer

or the like will be transmitted by the said lugs directly to the form or support upon which the socket rests and will not tend to break or damage the securing ears. It will be seen further from Fig. 1 that the socket is provided both exteriorly and interiorly with locking projections or ridges 8, 9 to resist shearing or displacement in the concrete. The flanged inner end of the socket is shown as frusto-conical and of considerable diameter to afford ample anchorage to the socket, thus resisting withdrawal or displacement from or in the concrete mass. The flange is further strengthened in its inner face by annular locking ribs 10 which increase the hold of the concrete upon the socket.

In Fig. 3, I have shown a shorter socket better adapted for use in thinner masses of concrete. This socket may be used vertically, horizontally or otherwise and in lieu of the threaded portion 3 there may be provided at or near its outer end any other desired attaching means by which to attach the member desired to be secured to the concrete.

My invention, herein described, makes it possible to materially reduce the weight and resultant cost of sockets without diminishing their tensile strength, and at the same time, increase their gripping power and resistance to shear in the concrete. My invention, furthermore, is not limited to the precise embodiment here shown for purposes of illustration, but contemplates a free substitution of elements performing similar functions.

I claim as my invention:—

1. A hollow attaching socket for concrete construction, having both exteriorly and interiorly located means for resisting shear, the hollow in said socket opening toward the rear to permit said interiorly located means to exert a tensional strain upon the concrete back of the socket, whereby the shear-resisting tendency of the socket is greatly increased without any substantial increase of metal.

2. A hollow attaching socket for concrete construction having a threaded end, interiorly located means for resisting shear, and a transverse partition between the threaded end and the said shear resisting means, the hollow in said socket opening toward the rear to permit said interiorly located means

to exert a tensional strain upon the concrete back of the socket, whereby the shear-resisting tendency of the socket is greatly increased without any substantial increase of metal.

3. A hollow attaching socket for concrete construction, having a threaded end, a flanged end provided with interiorly projecting annular ribs and a transverse partition between the threaded end and the flanged end.

4. A hollow socket for concrete construction having exteriorly located means normally adapted to produce lines of shear in

the concrete surrounding the sides of the 15 socket, and interiorly located means adapted to exert tensional strain in the concrete behind the socket, thus moving the lines of shear farther back in the concrete and greatly increasing the shear-resisting tendency of the socket. 20

In testimony whereof, I have signed my name to this specification, in the presence of two subscribing witnesses.

DAVID W. BROOKS.
